UNITED STATES PATENT OFFICE.

FRITZ R. FREDERICK, OF NEW YORK, N. Y., ASSIGNOR TO EDWARD STEVENS BEACHE, OF RIDGEFIELD, CONNECTICUT.

TYPEWRITER.

Application filed December 13, 1922. Serial No. 606,750.

To all whom it may concern:

Be it known that I, FRITZ R. FREDERICK, a citizen of the United States, and resident of New York city, in the county of New York and State of New York, have invented certain new and useful Improvements in Typewriters, of which the following is a specification.

This invention relates to typewriters. Its object is to produce, at low manufacturing cost, a very compact and quite silently operable typewriting machine of either light or heavy weight, having, by preference, a platen roll of large diameter and, by preference, a standard, four-bank key-board comprising forty-two impression key levers with associated type heads having two printing characters each, the machine being provided with a single case shifting mechanism having, by preference, two shift keys. A particular object of the invention is to make a typewriter of low dimension from base to top and to construct the typing units, each comprising a type head, an impression key lever and intermediate operating connections, in suchwise that the outermost impression key levers, in particular, will have comparatively little lateral deflection in the course of their lengths and thereby secure a satisfactory and efficient working connection between each type head and its impression key lever, whereby there is obviated that blurring by the imprinting characters on the outermost type heads which is apt to occur when the lateral deflection of the impression key levers adjacent their several connections with an associated type head is excessive.

Other objects of the invention are to reduce the cost of manual assemblage of the machine parts; so to construct said intermediate operating connections between each impression key lever and its associated type head that the type head will be caused to print by compression as distinguished from percussion, being moved to and from impression by toggle link connections which preferably, but not necessarily, are prevented from dead centering at the time of impression, whereby the use of special adjusting devices for each typing unit to vary the distance between a front toggle link pivot and the impression point on the platen may be eliminated. In the present embodiment of the invention, the front toggle links have a common stationary pivot rod, and the pre-

vention of the dead centering is obtained merely by dimensioning the framework of the machine so that the distance between the impression point and the stationary pivot rod of the front toggle links is less than the length of each front and back toggle link and therewith connected type head when the same are in alinement with the toggle links in dead centering position. Nevertheless, if it is desired to embody the present invention in a machine having the dead centering toggle link construction of the prior art, then the framework may be made enough longer to permit the dead centering at the time of impression or such result, if desired, may be accomplished in other and well known ways.

Another object of the invention is to arrange, in a four-bank key-board machine having the impression key tops in four parallel lines, an under and an upper tier, or series, of type heads, twenty-one type heads being mountable in the under tier and twenty-one type heads in the upper tier. By this arrangement the large number of type heads have a very compact lateral grouping and although the toggle link members of said operating connections are contractible and distensible, yet, in accordance with one of the objects of this invention, the toggle links associated with the under series of type heads project upwardly and the toggle links associated with the upper series of type heads project downwardly, whereby vertical compactness is obtained.

Another object of the invention is to construct the machine with many of the operating parts as close to its base as mechanical conditions permit.

So far as practicable, all the parts of the machine are made of die-formed sheet metal, and when hereinafter parts are referred to as being fixed, it is to be understood that they are fixed either by welding, brazing, screwing, riveting or in some other efficient mechanical means.

In the accompanying drawings, forming a part hereof and illustrating the principle of the invention in the best mode now known to me of applying that principle,

Fig. 1 is a partial sectional elevation from the front to the back of the open top sheet metal rectangular box frame in a line corresponding to line 1-1 of Fig. 10, looking towards the left hand of the machine and showing one of two single case shift levers

in connection with an upwardly swingable carriage rail and thereon mounted paper carriage comprising a platen roll.

Fig. 2 is a central sectional elevation of the machine at a line corresponding to line 2-2 of Fig. 10 and shows the general construction and operating relations of two tiers of type heads each provided with two printing characters.

Fig. 3 is a perspective view of the thin sheet metal cover, and indicates the working position of one of two transversely aligned ink ribbon spools and of two spool post sleeves carried by the cover.

Fig. 4 is a perspective view, partially broken away for greater clearness, of the intermediate thin sheet metal assembly bracket having transverse arced under and upper front toggle link pivot rods and guide combs for members of the operating connections between the impression key levers and type heads, and also showing an upwardly and rearwardly inclined, approximately triangular, integral supporting plate for the under type heads.

Fig. 5 is a perspective view of the bottom open top box frame of the machine, also of thin sheet metal.

Fig. 6 is a side elevation of the machine.

Fig. 7 is a partial front elevation of one of the guide combs carried by the assembly bracket.

Fig. 8 is a perspective view of the sheet metal, vibratable universal bar and dog-carrying plate.

Fig. 9 is a top plan view partly in horizontal section at line 9-9 of Fig. 6 of the right hand portion of the machine with the paper carriage broken away; and showing two of the upper type heads their respective impression key levers and operating connections in positions of rest; and diagrammatically indicating some of the impression key levers, other type heads and operating connections. The view is complementary to Fig. 3 and shows a portion of the cover in place.

Fig. 10 is a top plan view partly in horizontal section at line 9-9 of Fig. 6 of the left hand portion of the machine with the cover, paper carriage and upper tier of type heads and their connections removed, and shows diagrammatically the arcuate mounting of the type heads and the varying configurations of their respective impression key levers terminating at the front of the machine in a four bank key-board.

Fig. 11 is a detached view of the left hand end portion of the platen roll and its carrier broken off and also shows adjustable marginal stop means.

Fig. 12 is a plan view showing the ink ribbon spool rotating mechanism in detail.

Fig. 13 is a partial front elevation of the rear comb guide, with the universal spring

supporting shelf in place and is partially in transverse vertical section at line 13-13 of Fig. 10.

Fig. 14 is an under plan view of the rear end portion of the universal bar and dog-carrying plate and shows the under rigid dog in working relation to an escapement wheel tooth.

Fig. 15 is an elevational detail of the ink ribbon spool rotating mechanism.

In the drawings, the box frame (Fig. 5) has a flat bottom 1, a front side 2 which is vertically slotted from its upper edge downwardly at 2^a to form guide slots for actuating levers projecting forwardly through the slots and laterally guided by the side walls of the slots. The box corners are fixed together to stiffen the box frame, the base of which may be cut out to a considerable extent, if so desired, to reduce its weight. The box ends 3 and 4 at their rear end portions have upwardly slanting edges α their upper edges being downwardly recessed at 5 to permit endwise projection of the platen roll carrier. Rearwardly of these recesses the box ends have upstanding, transversely opposed portions 6 the upper ends of which are formed with journal bearings 6^a. The rear side of the box is indicated by 7.

In the journal bearings 6^a the ends of a transverse case shift rocker shaft 8 are mounted forwardly of but adjacent the rear side of the box (Figs. 9, 10 and 2). This rocker shaft is provided, near each end portion and as frequently thereinbetween as desired, with fixed short, horizontal, forwardly projecting brackets 9, each having at its front end portion an upstanding post 10 on which an anti-friction roll 11 is horizontally mounted. The back and front peripheral surfaces of such transverse row of anti-friction rolls are respectively aligned.

At each end portion, adjacent an end wall of the box frame, the rocker shaft 8 is provided with a fixed, dependent, L-shaped rocker arm, the vertical portion of which is indicated by 12 and the forwardly right angular extension of which is indicated by 13. The under edges of the extensions 13 are spaced apart from but are adjacent the box frame base.

Between their ends the upper edges of the extensions 13 have angular recesses 14 in transverse alinement one with another.

Such recesses have fixed to their divergent walls a transverse carriage rail which is lengthwise troughed. It has a bottom 15, a back wall 16 and front wall lugs 17, the wall 16 and the lugs 17 being parallel and at right angles to the bottom. The bottom and rear walls are fixed to the extensions 13 with the back wall slanting upwardly and rearwardly and the wall 15 slanting upwardly and forwardly and the front wall lugs 17 slanting upwardly and rearwardly.

A series of anti-friction balls 18 is mounted in the rear, angular portion of the troughed rail with their front peripheral surfaces in alinement and spacedly apart 5 from the front wall lugs 17.

The front end of each rocker arm extension 13 (Fig. 1) is provided with an inwardly projecting horizontal pin 19 which is received in the space between the upper 10 and under fork arms 20 at the rearward end of a case shift lever 21 which, forwardly of its rear end and between its ends, is pivoted at 22 above the box frame base to a short upstanding bracket 23, the foot 24 of which 15 is fixed to the base; the lever extending adjacent the box frame base forwardly through a guide slot 25 in the front side of the box frame.

As shown, there are two of these case shift 20 levers, one at the right hand corner of the key-board and the other at its left hand corner, the key top of each of these levers being lettered "Case shift." The carriage rail is movable for case shifting in the arc 25 of a circle the center of which is the axis of the case shift rocker shaft 8, shown tubular.

The rack engaging pinion and escapement wheel are located between horizontal extensions 13 and rearwardly of the carriage rail 20 which ties the connections 13 together and also braces them apart. A vertical post 25 fixed to the base (Fig. 2) carries the horizontal escapement wheel 26 spaced slightly apart but adjacent the box frame base, the 25 rack engaging pinion 27, revoluble with the escapement wheel, being carried by the upper portion of the post.

Spaced slightly above but adjacent the box frame base, a universal bar and dog 20 carrying frame plate 28 having between its ends transversely opposed upstanding ears 29 is pivoted in flatwise opposition to the box frame base on a transverse shaft 30, the ends of which are journaled in transversely 45 opposed upstanding brackets 31 fixed to the base. A quick-acting, coiled spring 32 encloses the shaft and has one end 33 anchored in the frame, its other end encircling the shaft and being anchored to a bracket at 34. The pivoted frame is flatwise vibratable 50 against the resistance of the spring.

The straight front edge of the frame plate 28 is transversely formed into an upstanding rib which forms the universal bar 32.

Rearwardly of the pivot rod, the frame 55 plate 28 is narrowed into a tongue 28^a which extends rearwardly towards the front periphery of the escapement wheel. This tongue is provided with an upper dog 35 that is pivoted at 36 to the upper surface of the tongue 28^a which is vibratable in flatwise opposition to the base adjacently the same. A wiper cam 37 is provided for the dog 35 and is held up to its work by a coiled spring 38, one end of which is fixed to the wiper 65

cam at 39 and the other end of which is fixed to the tongue at 40. An under rigid dog 35^a is also carried by the tongue and the two dogs are alternately vibrated in the vertical direction between the teeth of the escapement wheel.

The transverse pinion engaging rack 41 has its rack engaging teeth on its rearward edge and the rack is supported rearwardly of the carriage rail and forwards of the pinion (Figs. 2 and 6) by the under ends 70 of a pair of upstanding arms 42 each of which is pivoted at 43 to an end lug of the platen roll carrier. Both arms 42 extend 75 upwardly to form carriage release levers 44 each one at one end and the other at the other end of the platen roll carrier, the two forwardly projecting parallel end lugs of which are indicated by 45 and the concavo-convex 80 lengthwise extending back of which is indicated by 46.

The upper front marginal portion 47 of the transverse back 46 which forms a portion of the paper guard is vertical and flat 85 and is turned horizontally rearwards at 48 and then downwardly at 49, the wall portions 47 and 49 being parallel and dimensioned to make a sliding fit on the anti-friction rollers 11 carried from the carriage 90 shift rocker shaft 8.

The wall portions 47, 48 and 49 form a transversely extending truss resistant to type head pressures.

The under transverse marginal portion of the back 46 is formed into an inverted V-shaped trough 50, the under walls of which bear on the anti-friction balls carried by the troughed carriage roll, the front, downwardly and forwardly inclined wall 50^a of the inverted trough member 50 being a 100 sliding fit between forward peripheries of the anti-friction balls and the upwardly and rearwardly inclined front trough wall lugs 17 of the carriage rail which has closed 105 ends to keep the anti-friction balls in place.

The inverted V-shaped trough wall 50 of the platen carrier is made without ends, whereby the platen carrier may, at either end of the machine, move into endwise projection.

By the overlapping of the forward trough wall lugs 17 of the rail and of the platen roll trough wall 50^a the platen roll carrier is prevented from vertical displacement and the carrier rides on the anti-friction balls 120 transversely of the machine, its upper marginal portion being supported by the front peripheries of the anti-friction rollers 11.

The platen roll P has its trunnions 51 journaled in the forwardly projecting end 125 lugs 45.

The carriage release levers 44 are each normally held forwards above its pivot 48 by a coiled spring 44^a the front end of which is fixed at 52 to a lug 45 and the rear- 130

ward end of which is fixed to a carriage release lever at 53.

These springs 44^a hold the teeth of the rack 41 in normal engagement with the 5 teeth of the pinion 27.

The back 46 is provided with a rearwardly projecting fixed pin 54 for connection by a connector, not shown but well known, with the periphery of the carriage spring drum 10 55 which is pivoted on a horizontal post 56 projecting from a horizontal inwardly extending bracket 57 carried by the dependent member 12 of the left hand rail carrying rocker arm. The carriage spring drum thus 15 has a rockable movement during case shifting movements and is carried by the case shifting mechanism rearwardly of the path of the platen roll and is located favorably to the desired compact structure of the machine.

Forwardly of the front ends of the rocker arm extensions 13 the box frame is provided with a fixed, transversely extending, up-standing rear comb guide 58 having midway 25 between its ends a forwardly and downwardly slanting lug 59 at its upper edge.

The transverse, horizontal foot-forming web 60 of this comb guide is fixed to the box frame base, and its under margin, between its ends, is recessed at 58^a (Fig. 13) and the upper edge margin of the comb guide, above the recess, is vertically slotted at 61 to form a series of guide slots for the rear end of each impression key lever and 35 also for the rear end of each of the two side bar levers of the spacing key frame mentioned below. Each end of the comb guide is also vertically slotted at 21^a for passage therethrough of each of the shift 40 key levers.

The recess 58^a is horizontally spanned by a horizontal, forwardly projecting shelf 62 having a vertical back web 62^a, the ends of which are fixed to the comb guide 58, the 45 upper edge of the web being spaced below the under ends of the guide slots 61 and the under side of the shelf being spaced above the under foot-forming web 60 and the box frame base 1 to permit free passage there- 50 through and vertical movement of the dog carrying end of the universal bar and dog carrying frame 28.

On the shelf 62 there is fixed the flat bottom web 63 of a transverse universal spring 55 provided with a series of upwardly and rearwardly curved spring teeth 63^a, the free end of each of which bears against the under edge of each impression key lever and of each side arm lever of said spacing key 60 structure.

The spacing key levers are indicated by 64 (Figs. 9 and 10) and are parallel one to another and form the side bars of a U-shaped frame, the front transverse portion 65 of which extends along the front of the

key-board and has between its ends a transversely extending, horizontal lip forming the spacing key S.

The upper edge of the end portion of each impression key lever and of each side bar 70 lever 64 is recessed as sufficiently indicated at 65^a (Fig. 2) to form a bearing for a pivot that is formed by the upper end wall of a vertical guide slot 61. The ends of said levers pass rearwardly through the 75 guide slots and forwardly of the comb guide 58; the under edge of each lever is pressed upwardly by the free end of a spring tooth 63^a whereby each recessed bearing is kept in working engagement with a pivot forming wall 61^a. This universal lever retaining spring is a feature of the economic assem- 80 blage of the machine.

The impression key levers 66 and 67 preferably alternate. Each impression key lever 85 66 (Fig. 2) adjacent but inwardly of the front wall of the box frame has an up-standing link pivoted to it at 66^a and is operatively connected with an upper endwise movable but downwardly and rearwardly 90 inclined type bar 66^b which, at its rear end, is provided with a type head 66^c having two printing characters.

Each impression key lever 67 has piv- 95 otally connected to it at 67^a an upstanding link and is operatively connected with an under, upwardly and rearwardly inclined type bar 67^b provided at its rear end with a type head 67^c having two printing characters.

The impression key levers extend from their pivoted rear ends forwardly in parallelism one to another, as indicated dia- 100 grammatically by 68 in Fig. 10, these parallel portions severally merging into out- 105 wardly and forwardly slanted portions 68^a which are also parallel one to another and spaced apart, and are most pronounced in the impression keys at the right and left hand ends of the machine, the degree of 110 inclination varying according to the distance of the impression key lever from the middle key lever of the assemblage. Each slanted or inclined portion 68^a forwardly 115 of the front wall of the box frame merges into a straight portion passing through a guide slot 2^a, these straight portions being parallel one to another. By locating the type bars in an under and upper series, the impression key levers, spaced laterally 120 apart, are brought into such positions relatively to the type bars that each may have an efficient and substantially vertical direct mechanical connection with its type bar. The under edges of all the type bars 125 bear normally on the universal bar 32^a.

The type bars 66 and 67 preferably alter- 130 nate between the machine ends, as indicated in Fig. 10, and the operating connections between each impression key lever and its

associated type bar are severally opposed to a space between two adjacent key levers at the front side of the machine, the operating connections between the impression key levers associated with the under type bars extending upwardly and working between two adjacent impression key levers.

The cover (Fig. 3) comprises a front, horizontal, transverse web 69 having fixed to its under surface a transverse cushioning pad 69^a against the under side of which all the impression key levers bear when in their positions of rest and against which they strike on their return from depressed positions. The cover comprises, above the web 69, a vertical upstanding front wall 70 at the upper edge of which the cover forming metal extends rearwardly in a top 71 the front marginal portion of which is flat and the rear marginal portion of which slopes downwardly towards the platen roll and has its rearward edge recessed at X' for better visibility of a line being printed. The cover has integrally dependent, rearwardly converging sides 73 each of which merges in a horizontal plate or wing 74 that horizontally covers the machine at each side of a vertical side 73. Each plate or wing extends rearwardly into an upturned marginal portion 75 to match and bear on the frame end portions α , and each wing has a dependent flange 76. The ends of the front vertical wall 70 are provided with dependent legs 77, each provided with a screw hole 78, and each flange 78^a is provided with screw holes whereby the cover is fixed to the box frame at its front by screws 79 through the holes 78 into the holes in the front wall of the box frame; the flanges 76 being fixed to the box frame ends by screws 80.

The intermediate assembly bracket (Fig. 4) comprises an upwardly and rearwardly inclined under type head guiding plate 81 which converges rearwardly to an apical end 81^a that is fixed to the lug 59 of the rear comb plate 58. The plate 81 has upstanding rearwardly converging sides 82 that terminate forwardly of its rear apical portion. Each side 82 terminates in a downwardly extending leg 83 having a horizontal flange 84 provided with a rivet hole 84^a whereby the legs are attached to the bottom of the box frame at 85. The rear end portions of the sides 82 carry an under arcuate upstanding comb guide 86 and the upper margins of the sides 82 carry a corresponding upper comb guide 86^a. The under comb guide has a downwardly and rearwardly slanting flange 86^b fixed to the plate 81. The upper comb guide 86^a has an upwardly and forwardly slanting flange 86^c in line with the rearwardly and downwardly slanting top edges of the sides 82. The rear edge of the plate 81 is transversely arced and for-

wardly of such edge the assembly bracket carries an arcuate, under front toggle link pivot rod 87 spaced above which the sides carry an arcuate transverse upper front toggle link pivot rod 88. Forwardly of and adjacent the upper pivot rod, the sides 82 carry a transverse arcuate upper comb guide having a top flange 89 flush with the top edges of the sides 82, the flange having a downwardly extending comb guide 89^a, the vertical slots in which are indicated by 90. The forward and rearward comb guides carried by the assembly bracket have similar slots. The pivot rods 87 and 88 are also supported by hooked brackets 91 (Figs. 2 and 9) the bends of which vertically enclose the pivot rods and the vertical shanks 92 of which are secured to comb guides in front of the pivot rods, the upper brackets 91 being secured to the comb guide 89^a and the under brackets being secured to a transverse, arcuate comb guide 93 carried by the sides 82 just forwardly of the under pivot rod 87. The ends of the comb guide 93 are secured to the sides 82. Intermediate the front comb guides 89^a and 93 and the rear comb guides 86 and 86^a, the frame sides 82 carry an upper flanged comb guide, the rearwardly and downwardly slanting flange of which is indicated by 94. This comb guide is arcuate and is spaced above an under arcuate comb guide 95 having a flange fixed to the plate 81.

Between the rear comb guides 86 and 86^a and spaced apart from each thereof, the sides 82 carry a transverse, arcuate comb guide the under margin of which has vertical guide slots 96 and the upper margin of which has vertical guide slots 96^a. The flanges 86^c, 94 and 89 serve to support the downwardly and rearwardly slanting rear portion of the cover top. The under comb guide 93 is spaced forwardly of the front edge of the plate 81 to form a space y up through which from impression key levers 110 the links which connect the front toggle links associated with the under type heads extend.

The legs 83 of the assembly bracket straddle the under mentioned assemblage of impression key levers and also the vibrating universal bar and dog carrying plate 28, and support the plate 81 above the box frame base forming a clear space 97 in which rearward portions of the impression key levers and of the plate 28 are free to vibrate. The under ends 98 of the under series of type heads 67^c are upwardly and rearwardly slanted and slide on the plate 81.

Each of the under type heads 67^c has two vertically aligned printing characters, the under character being indicated by a and the upper by b . Each under type head has a forwardly and downwardly extending bar 67^b having parallel upper and under edges, 130

the under edge being above the under edge of the type head end 98.

The forward portion of each under type bar 67^b has a reentrant, lengthwise extending slot 99 whereby the forward end of the bar is forked; the under fork arm being indicated by 100 and the upper fork arm by 101.

Each upper type head 66^c has a rearwardly and upwardly inclined bar 66^b the forward end portion of which has a reentrant, lengthwise extending slot 99^a whereby the forward ends of the upper type bars are also forked and the fork arms of which are indicated by 100^a and 101^a.

Referring to Fig. 4, the intermediate guide comb structures 94 and 95 are practically reversible identical structures. As shown in Fig. 7, in connection with the upper guide comb structure (see also Fig. 2) the vertical comb guides are formed with two guide openings 102 and 103 for each type bar, the guide opening 102 being four-sided for reception of either of the two cross-sectionally similar fork arms 99 or 99^a and the guide opening 103 having marginal slots for reception of a margin of the wider fork arm adjacent a fork space. As seen in Fig. 2, the upper guide comb 94 supports the forked forward portions of the upper type bars 66^b and the under guide comb supports the forward forked portions of the under type bars 67^b. The rearward portions of the upper type bars are supported by the upper guide comb 86^a and by the upper portion of the intermediate guide comb 96 while the under type bars 67^b have their forward portions supported by the under marginal portion of the intermediate guide comb 96, by the upper marginal portion of the guide comb 86 and by the sliding contact of their under ends 98 on the plate 81. The arrangement is such that the under and upper type bars considered in their vertical arrangement, converge towards the platen. They also, considered in plan arrangement, converge in the direction of the platen, being radially movable to and from impression.

Each under type bar 67^b has pivoted to it between its ends at 104 an upwardly and forwardly extending rear toggle link 105 the upper forward end of which is pivoted at 106 to the upper end of an upstanding front toggle link 107 the under end portion of which is pivoted on the under pivot rod 87. Each under front toggle link 107 has a rearwardly extending projection 107^a above and rearwardly of its pivotal connection to the pivot rod 87. And each projection 107^a has pivoted to it at 108 the upper end of a dependent link 109 which is pivoted to an impression lever 67 at 67^a. Consequently, depression of the front end of an impression lever 67 drives an under

type bar 67^b upwardly, rearwardly and radially to impression. Each under type bar 67^b has a coiled return spring 110 connected to it at 111, the forward end of the return spring being attached to the comb 70 plate 93 at 112.

Each upper type bar 66^b has pivoted to it between its ends at 113 a downwardly and forwardly extending rear toggle link 114, the under forward end of which is pivoted at 115 to the under end of a downwardly extending front toggle link 116, the upper portion of which is pivoted on the upper pivot rod 88, this front toggle link 116 having an end portion 117 projecting upwardly and forwardly from the pivot rod 88 and such extension 117 having a pivotal connection at 118 with a dependent link 119 which is pivotally connected to an impression key lever 66 at 66^a. Consequently, depression of a key lever 66 will move the mid-sectional pivot joint 115 of the toggle links 116 and 114 upwardly with the result of sliding the upper type bar 66^b downwardly and rearwardly to impression. Each upper type bar 66^b has a return spring 120 connected to it at 121, the rear end of the return spring being fixed at 122 to the guide comb 89^a.

Each under printing character *a* on each under type head 67^c and each under printing character *a'* on each upper type head 66^c is aimed at the impression point when the platen is in its lowermost position; and each upper printing character *b* on each under type head 67^c and each upper printing character *b'* on each upper type head 66^c is aimed at the impression point when the platen is case shifted into its upper position indicated by a dotted line in Fig. 2.

The type bars are endwise reciprocable with little friction, having easy sliding contact with the guiding and supporting surfaces of the comb guides by which they are laterally guided to and from impression, and at impression each type head is positively guided by a four-walled type head guide 123 upstanding from and fixed to the apical rearward end 81^a of the assembly bracket, type head guide plate 81.

Ink ribbon spool sleeves 124 are transversely and upstandingly fixed in the frame plates or wings 74 projecting upwardly above and downwardly below such wings (Figs. 3 and 15). The spool heads 125 are supported on the upper ends of the sleeves above the wings 74.

Spaced apart, upstanding, vertically slotted ink ribbon guides are fixed to the upturned margin 75 of the cover, one guide 125 being at each side of the impression point. The ink ribbon R runs from one spool to the other. An endwise movable slide bar 127, Figs. 12 and 15, is mounted in the box frame ends 3 and 4 between the vibratory

universal bar and dog-carrying frame plate 28 and the wings of the cover. The slide bar is provided between the box frame ends with spaced apart forwardly projecting horizontal lugs 128 for severally engaging transversely spaced apart, upstanding left spring feed pawls, each having an outwardly projecting tooth 129 from the upstanding member 130 of the pawl which has a foot 131 fixed to a side margin of the plate 28. Each box frame end carries an inwardly projecting horizontal spring pawl 132, the outward end of which is fixed at 133 to a box frame end. Each spring pawl 132 is provided towards its inward free end with a forwardly projecting tooth 134 and the free end of each pawl 132 is bent forwardly at 135. The rear edge of the slide bar 127 is provided on its rear edge outwardly of a lug 128 in the direction of a box frame end with a rearward projection 136 which is recessed forwardly at 137. For each ink ribbon spool there is provided a ratchet wheel 138 that is provided with peripheral teeth 139 which point, viewing the ratchet wheels in top plan view, in the clockwise direction. Each ratchet wheel 138 is fixed on the under end of a vertical stud 140 which passes upwardly through a sleeve 124 and has the ink ribbon spool body fixed to it in the well known way. The spring pawls 132 are check pawls. The members 130 are spring feed pawls.

Noting that the ink ribbon spool ratchet wheels 138 have their teeth pointing in the clockwise direction when viewed in top plan and that the plate 28 carries the feed pawls 130 forwardly of its shaft 30 the operation of the ink ribbon actuating mechanism is as follows: With the slide 127 adjusted in its left hand position, as indicated, then the right hand lug 128 is in position to hold the right hand feed pawl 130 out of contact with the right hand ratchet wheel. The right hand lug 128 engages the right hand side of the right hand pawl 130 and the left hand lug 128 engages the left hand side of the left hand pawl 130. The left hand lug 128 will permit the left hand pawl 130 to spring to the left and push its tooth 129 into feeding contact with a tooth of the left hand ratchet wheel. The upstrokes of the left hand feed pawl automatically push on the teeth of the left hand feed pawl ratchet wheel with the result of winding up the ribbon on the left hand spool automatically. To prevent retrograde movement of either of the spools the spring check pawls 132 are provided with the teeth 134 which engage the teeth 139 on the ratchet wheels. The end bends 135 on the check pawls 132 are alternately engaged by the lugs 136 on the slide bar 127. As the position of the slide 127 permits feeding of the left hand spool, the

left hand lug 136 permits the left hand check pawl 132 to engage the left hand ratchet wheel and hold it against retrograde movement. At the same time, the right hand lug 136 of the slide bar will cause the right hand check pawl 132 to be disengaged from the right hand ratchet wheel so as to permit free rotation of the right hand spool 125.

In order to hold the slide 127 in either its left or right hand position, the lugs 136 are severally provided with the recess 137 into which the bent ends 135 of the check pawls 132 automatically seat themselves alternately, depending on the endwise adjustment of the slide 127.

For winding the ink ribbon from the left hand spool on to the right hand spool, the slide bar is shifted to the right and the machine then operated until the ribbon is wound up, the winding up operation being automatic. When the ink ribbon has been wound up on the right hand spool the slide bar 127 is adjusted to the left and automatically held in its adjusted position by the check pawls 132.

The platen roll carrier is shown provided with the usual pivoted detent roll carrier 141 provided with a detent roll 142 cooperating with a toothed wheel 142^a fixed on a platen roll trunnion.

The front paper guides for the platen roll are shown at 143 and the paper feed roll for the carriage is indicated by 144.

The marginal stop device comprises a horizontally forwardly flanged bar 145 fixed to the upper wall 48 of the platen roll carrier back 46. This flange 145 extends vertically upwards forming a wall 5 which may be calibrated and the flange then slants upwardly and rearwardly at 146, forming a lengthwise web which has a lengthwise extending slot 147 for reception of the shank of a stud 148. The stud 148 has fixed to it upwardly of its downwardly and rearwardly slanting back end a clamp nut 149 which bears against the back side of the slanted portion of the flange. A flanged washer 150 has a flat portion that bears on the forward surface of the slanted flange 146. A knurled nut 151 is threaded on the upper projecting end of the post 148 for clamping the marginal stop structure in adjusted position at any place along the length of the slot 147. The platen shift rocker shaft 8 has at its right and left hand portions a fixed upwardly projecting stop 152 rising upwardly, whatever be the position of the case shift table paper carriage, into the path of the under backward end of a post 148. Two of these marginal shift stops are shown (Figs. 9 and 11), one at the left hand end and the other at the right hand end of the paper carriage.

Various changes in mechanism may be made without departure from the principle of this invention. An important object of this invention is to make a standard four-bank typewriting machine of extremely low height and provided with a platen roll of as large a diameter as is customary in large sized typewriting machines for office and commercial uses. It will be observed from 5 the drawings that the platen roll when in either its lower or upper case shifted position has its impression point at a greater distance from each of the front toggle link pivot rods than is the combined length of 10 each front toggle link and its connected rear toggle link and type bar from the front pivot rod to the faces of the printing characters; and hence whenever a type head is 15 thrust to impression, the toggle links comprised in the operating connections between 20 such type head and the associated impression key lever are prevented from dead-centering. The result is, in this preferable 25 but not necessary construction, that a large 30 number of parts are eliminated from the mechanical construction and the impression while compressively exerted is constantly under the touch of the operator and 35 is not mechanically limited as would be the case if toggle links were permitted to dead center at the time of impression. While 40 the quick acting coiled spring 32 of the universal bar and dog-carrying frame serves 45 to return a depressed impression key lever, 50 in consequence of the upward movement of the universal bar when pressure is taken off the depressed key lever, the upward return movement of the depressed key lever effecting a return to normal position of rest 55 of the associated type head and toggle link 60 connections, yet it is preferred, in order to quicken the return movement of the members of the typing unit to provide each end-wise moving type bar with a return spring 65 by connecting such return spring to the type 70 bar and a stationary part of the machine.

The under pivot rod 67 and the upper pivot rod 68 severally constitute a pivot forming main support for an actuating 75 mechanism between a type bar and its associated impression key lever. These two pivot forming members 67 and 68 are spaced apart one at one side and the other at the other side of a plane projectable through 80 the axis of the platen in whatever position it may be relatively to the impression characters.

What I claim is:

1. In a typewriting machine, the combination of a frame; a detachable cover; and an intermediate assembly bracket; a case shifting mechanism; a spacing mechanism; a series of typing units provided with under type heads; a series of typing units 85 provided with upper type heads; for each

of said under type heads, type head guiding means comprised in said assembly bracket; for each of the upper type heads, type head guiding means comprised in the assembly bracket; transversely opposed ink 70 ribbon spool carrying means secured to the cover; ink ribbon spool rotating means; and a paper carriage provided with an end-wise movable platen.

2. In a typewriting machine comprising 75 a series of typing units some of which have under type heads and others of which have upper type heads, the combination of an open top frame; a transverse case shift rocker shaft carried by said frame; a paper 80 carriage operatively connected with said rocker shaft; a key controlled case shift mechanism operatively mounted adjacent the frame base; a horizontal escapement wheel and upstanding rack engaging pinion 85 supported by said base rearwardly of the paper carriage path; forwardly of the paper carriage path an upstanding comb guide vertically slotted for reception of the rear 90 ends of impression key levers; a shift key lever and a spacing key lever; the front wall of the frame being a vertically slotted comb guide for forward projection through the slots of such key levers; and a vibratable universal bar and dog carrying frame 95 pivoted closely adjacent the frame base, between the base and the impression key levers.

3. In a typewriting machine, the combination of a paper carriage with a series 100 of typing units each comprising a pair of toggle links, and some of which units comprise an under series of type heads having a plurality of printing characters and others of which comprise an upper series 105 of type heads having a plurality of printing characters; bodily immovable mechanism for guiding the under series of type heads to and from impression in upwardly and rearwardly inclined paths, and bodily immovable means for guiding the upper 110 type heads to and from impression in downwardly and rearwardly inclined paths; each pair of toggle links associated with an under type head comprising an upstandable, 115 front toggle link pivoted on a stationary pivot and having a rearward projection; said pivot; a link pivotally connected at its upper end with said projection and pivotally connected at its under end with an impression key lever; and such impression key lever; and each pair of toggle links associated with an upper type head comprising a dependent, front toggle link 120 pivoted on a stationary pivot and having a forward projection; said pivot; a link the upper end of which is pivotally connected to said forward projection of a dependent toggle link and the under end of which is pivotally connected to an impression key 125 130

lever; and such impression key lever; said front toggle links being mounted with their respective toggle link carrying end portions opposable one to another transversely of the machine.

4. In a typewriting machine, the combination of a paper carriage with a series of typing units, some of which comprise an under series of type heads having a plurality of 10 printing characters and others of which comprise an upper series of type heads having a plurality of printing characters; mechanism for guiding the under series of type heads to and from impression in upwardly and rearwardly inclined paths, and means for guiding the upper type heads to and from impression in downwardly and rearwardly inclined paths; each typing unit comprising a type head, a rear toggle link, 20 a front toggle link and a pivoted link connecting the front toggle link with an impression key lever; the toggle links for the under type heads projecting upwardly and the toggle links for the upper type heads projecting downwardly when the type heads are in position of rest.

5. In a typewriting machine, the combination of a case shiftable paper carriage comprising a platen roll; a single, case shift 30 mechanism; a series of under typing units severally comprising an impression key lever; a type head having two printing characters and intermediate operating connections comprising a pair of upstanding 35 toggle links; stationary means for guiding each under type head to and from impression; a series of upper typing units severally comprising an impression key lever, a type head having two printing characters and a 40 pair of dependent toggle links; and stationary means for guiding each upper type head to and from impression; an open top frame in which the case shifting mechanism is mounted; an assembly bracket provided 45 with said guides and carrying the type heads and said operating connections, the assembly bracket being fixed in place.

6. In a typewriting machine, the combination of a case shiftable paper carriage comprising a platen roll; a single, case shift 50 mechanism; a series of under typing units severally comprising an impression key lever; a type head having two printing characters and intermediate operating connections comprising a pair of upstanding toggle 55 links; stationary means for guiding each under type head to and from impression; a series of upper typing units severally comprising an impression key lever, a type head 60 having two printing characters and a pair of dependent toggle links; and stationary means for guiding each upper type head to and from impression; an open top box frame in which the case shifting mechanism is 65 mounted; an assembly bracket provided

with said guides and carrying the type heads and said operating connections, the assembly bracket being fixed in place; and a cover constructed to cover the assembly bracket and a portion of the box frame, the 70 cover having rearwardly convergent upstanding sides.

7. In a typewriting machine, the combination of a platen carrier comprising a platen and a series of typing units some of 75 which comprise an under series of type heads having a plurality of printing characters and others of which comprise an upper series of type heads having a plurality of characters; bodily immovable mechanism 80 for guiding the under series of type heads to and from impression in upwardly and rearwardly inclined paths; bodily immovable means for guiding the upper type heads to and from impression in downwardly and 85 rearwardly inclined paths; each of the under type heads being operatively connected with a pair of toggle links comprising a front, upstanding member and a stationary pivot therefor; and each of the upper type 90 heads being operatively connected with a pair of toggle links each comprising a front toggle link and a stationary pivot therefor; a case shiftable paper carriage; an impression key lever operatively connected with 95 each front toggle link; said stationary pivots being spaced apart in the vertical direction, the toggle link carrying ends of the front toggle link for an under type head being 100 upstanding, the toggle link carrying end for an upper type head being dependent, said toggle link carrying ends of the upstanding and dependent toggle links being laterally opposable, the dependent portion 105 of the dependent toggle link having its under end pivotally connected to an upwardly and rearwardly extending rear toggle link pivoted to an upper type head, and the upper end of the upstanding front toggle link being pivotally connected with a downwardly and rearwardly extending, rear toggle link pivotally connected to an under type 110 head and said rearward toggle links being in cross-wise lateral relation one to another.

8. In a typewriting machine, the combination of an under series of upwardly and rearwardly inclined type head bars having two printing characters each; an upper series of downwardly and rearwardly inclined type head bars having two printing 115 characters each; bodily immovable, type head guiding means fixedly connected to the machine frame, laterally convergent in the rearward direction and spaced apart from the bottom and also from the sides of the 120 frame; and a machine frame having a bottom and upstanding side portions for each type head bar an impression key lever and operating connections comprising toggle links between the bar and lever; a single 125 130

- case shift paper carriage; and a single case shift mechanism; all the type bars being reciprocable in paths radial to impression and the impression key levers having key tops arranged in four parallel rows at the key-board.
9. In a typewriting machine, the combination of an under series of upwardly and rearwardly inclined type head bar having two printing characters each; an upper series of downwardly and rearwardly inclined type head bars having two printing characters each for each type head bar an impression key lever and operating connections comprising toggle links between the bar and lever; a single case shift paper carriage; and a single case shift mechanism; all the type bars being reciprocable in paths radial to impression and the impression key levers having key tops arranged in four parallel rows at the key-board.
10. In a typewriting machine, the combination of an under series of upwardly and rearwardly inclined type head bars having two printing characters each; an upper series of downwardly and rearwardly inclined type head bars having two printing characters each for each type head bar an impression key lever and operating connections comprising toggle links between the bar and lever; a single case shift paper carriage; and a single case shift mechanism; all the type bars being reciprocable in paths radial to impression and the impression key levers having key tops arranged in four parallel rows at the key-board; the paper carriage being bodily swingable for case shifting and comprising a carriage rail located closely adjacent the machine frame base; the frame base being provided with upstanding side portions; the bodily swingable paper carriage being pivotally supported at the rear of the machine above the base; and secured to the frame base between the upstanding side portions thereof, an upstanding bracket comprising fixed guides for said type head bars and being spaced apart from the upstanding side portions of the base and also spaced above the base.
11. In a typewriting machine, the combination of an under series of upwardly and rearwardly inclined type head bars having two printing characters each; an upper series of downwardly and rearwardly inclined type head bars having two printing characters each for each type head bar an impression key lever and operating connections comprising toggle links between the bar and lever; a single case shift paper carriage; and a single case shift mechanism; all the type bars being reciprocable in paths radial to impression and the impression key levers having key tops arranged in four parallel rows at the keyboard; the toggle links for the upper type bars extending downwardly and the toggle links for the under type bars extending upwardly; a machine frame; a therewith fixedly connected, upstanding bracket comprising bodily immovable, type head bar supporting and guiding means, said bracket being spaced apart from the bottom of the frame and rearwardly spaced apart from the front of the frame to provide a space forwardly of the bracket for type head actuating members.
12. A typewriting machine comprising in combination an open top frame; an assembly bracket and a cover having rearwardly convergent upstanding sides and a downwardly and rearwardly slanting top portion terminating forwardly of a paper carriage comprising a platen; such paper carriage; operating mechanism therefor including single case shifting means having an accessible case shift key; a series of upper type heads comprising two printing characters; a series of under type heads comprising two printing characters; for each type head an impression key lever and between it and its connected type head, compression printing type head operating means.
13. A typewriting machine comprising in combination an open top frame; an assembly bracket and a cover having rearwardly convergent upstanding sides and a downwardly and rearwardly slanting top portion terminating forwardly of a paper carriage comprising a platen; such paper carriage; operating mechanism therefor including case shifting means having an accessible case shift key; a series of upper type heads comprising two printing characters; a series of under type heads comprising two printing characters; for each type head an impression key lever and between it and its connected type head, compression printing type head operating means; such operating means severally comprising a pair of toggle links, the toggle links for the under type heads projecting upwardly and the toggle links for the upper type heads extending downwardly; and the accessible ends of the impression key levers being arranged in four parallel rows at the key-board.
14. In a typewriting machine comprising typewriting instrumentalities, the combination of an open top frame having a front vertically slotted guide comb side; at its rearward portion a case shift rocker shaft; dependent carriage rail carrying means for holding the carriage rail adjacent the frame bottom; a carriage rail secured on said

- means; adjacent the bottom a horizontal escapement wheel and a therewith revoluble upstanding rack-engaging pinion; such rack carried by the paper carriage; a vibratory 5 universal bar and dog carrying means mounted adjacent the bottom; an impression lever, rear guide comb plate, upstanding from the bottom; and impression key pivoting means adjacent the bottom.
- 10 15. In a typewriting machine comprising typewriting instrumentalities, the combination of an open top frame having a front vertically slotted guide comb side; at its rearward portion a case shift rocker shaft; 15 dependent carriage rail carrying means for holding the carriage rail adjacent the frame bottom; a carriage rail secured on said means; adjacent the bottom a horizontal escapement wheel and a therewith revoluble 20 upstanding rack-engaging pinion; such rack carried by the paper carriage; a vibratory universal bar and dog carrying means mounted adjacent the bottom; an impression lever, rear guide comb plate, upstanding 25 from the bottom; and impression key pivoting means adjacent the bottom; the rear guide comb plate and impression key pivoting means being located forwardly of the paper carriage rail.
- 30 16. In a typewriting machine comprising typewriting instrumentalities, the combination of an open top frame having a front vertically slotted guide comb side, at its rearward portion a case shift rocker shaft; dependent carriage rail carrying means for holding the carriage rail adjacent the frame bottom; a carriage rail secured on said means; adjacent the bottom a horizontal escapement wheel and a therewith revoluble 35 upstanding rack-engaging pinion; such rack carried by the paper carriage; a vibratory universal bar and dog carrying means mounted adjacent the bottom; an impression lever, rear guide comb plate, upstanding 40 from the bottom; and impression key pivoting means adjacent the bottom; the rear guide comb plate and impression key pivoting means being located forwardly of the paper carriage rail.
- 45 17. In a typewriting machine comprising typewriting instrumentalities, the combination of an open top frame having a front vertically slotted guide comb side, at its rearward portion a case shift rocker shaft; dependent carriage rail carrying means for holding the carriage rail adjacent the frame bottom; a carriage rail secured on said means; adjacent the bottom a horizontal escapement wheel and a therewith revoluble 50 endwise movable on the rail, the carriage comprising means for holding it and the rail in working position; the case shift rocker shaft comprising a plurality of forwardly projecting rocker arms severally provided 55 with a bearing for a therewith contacting member of the paper carriage and the carriage being formed with a member in slideable contact with the bearings carried by said rocker arms.
- 60 18. In a typewriting machine, the combination of a frame having a transverse front, vertically slotted, guide comb; a series of impression key levers severally mounted in one of such slots and fulcrumed at its 65 rearward end adjacent the frame bottom; a universal bar and escapement wheel dog carrying frame pivoted adjacent said bottom under the impression key levers; a transverse, horizontal, quick return spring for said frame; means for supporting and guiding to and from impression an upper series of type heads; means for supporting and guiding to and from the impression an under series of type heads; a bodily immovable bracket comprising said means; between each type head and its connected impression key lever, compression printing operating connections forwardly of said bracket; and a paper carriage.
- 70 19. In a typewriting machine the combination with a case shiftable paper carriage and case shifting mechanism of a series of upper endwise movable type bars; a series of under endwise movable type bars; an impression key lever for each of the type bars 75 and between each impression key lever and a type bar a toggle link operating mechanism; a universal bar carrying frame; a quick acting horizontal, transverse return spring therefor; and for each type bar a 80 coiled return spring having one end attached to a member of a typing unit and its other end connected to a stationary part of the frame; said horizontal, transverse, return spring cooperating with each of the 85 other springs for returning a depressed impression key lever to position of rest, and such other return springs severally maintaining all the typing units in position of rest with the exception of the typing unit 90 in operation; a bodily immovable bracket containing type head supporting and guiding means; the bracket being spaced above the bottom of the machine and the impression key levers having their rear ends 95 pivoted rearwardly of the front portion of the bracket and passing forwardly between the bracket and the universal bar carrying frame.
- 100 20. A typewriting machine comprising, in 105 combination, a plurality of under type heads; a plurality of upper type heads; an impression key lever for each type head; between each type head and its connected impression key lever operating connections 110 comprising a toggle link; the type heads severally having a plurality of printing characters and the impression key levers being severally provided with a key top, and the key tops being arranged in four parallel 115 rows; means for guiding the under type heads to and from impression; and means for guiding the upper type heads to and from impression; the toggle links connected with the upper type heads projecting downwardly, and the toggle links connected with the 120 under type heads extending upwardly and being arranged to cause the mid-joints of the toggle links connected with the under type heads to be above the mid-joints of the 125 130

toggle links connected with the upper type heads, and the mid-joints of the toggle links connected with the upper type heads to be below the mid-joints of the toggle links connected with the under type heads, when the type heads are in normal position of rest.

20. In a typewriting machine, the combination of a main frame; a stationary type-bar carrying frame; a case-shiftable platen; a series of under endwise reciprocal type-bars; a series of upper endwise reciprocal type-bars; and for each type-bar an impression key lever and operating connections between it and one of the type-bars, the type-bars being endwise movable in said carrying frame; each impression key lever, its associated type-bar and the operating connections between them forming a typing unit, and such typing units having the under type-bars alternating in the lateral direction with the typing units having the upper type-bars, said type-bar carrying frame being spaced above the impression key levers and comprising front corner members fixed to the frame base; said frame base; and for each typing unit an impression key lever located under said frame, pivoted rearwardly of the front end thereof and passing under and forwardly of said frame; and each typing unit comprising a rearwardly extending toggle link pivoted to a type bar, the toggle link for an upper type bar extending rearwardly and upwardly and the toggle link for an under type bar extending downwardly and rearwardly and such toggle links being in lateral, crosswise opposition when the typing units are at rest.
21. In a typewriting machine, the combination of a stationary machine frame having a transversely extending comb guide for forwardly projecting impression key levers; a type head guiding and supporting bracket fixed to said stationary frame; a case shiftable paper carriage comprising a platen; a single case shift mechanism; the impression key levers being arranged with key tops in four banks; an upper series of type heads each having two printing characters; an under series of type heads each having two printing characters; operatively connected with each type head an impression key lever; a link connecting such lever with the forward end of a front toggle link; said toggle link; and a rear toggle link pivoted to the rearward end of a front toggle link, the front end of which is pivoted to the type head, each such typing unit being constructed and operating to print by compression; means for maintaining each typing unit in a position of rest; means for returning each typing unit to a position of rest following its impression movement; and vertically spaced apart, bodily immovable pivots for the front toggle links, such pivots

being located forwardly of the bracket. 65

22. In a typewriting machine, the combination of a stationary machine frame having a transversely extending, comb guide for forwardly projecting impression key levers; a type head guiding and supporting bracket 70 fixed to said stationary frame; a case shiftable paper carriage comprising a platen; a single case shift mechanism; the impression key levers being arranged with key tops in four banks; an upper series of type heads 75 each having two printing characters; operatively connected with each type head an impression key lever; a link connecting such lever with the forward end of a front toggle link; said toggle link; and a rear toggle link 80 pivoted to the rearward end of a front toggle link, the front end of which is pivoted to the type head, each such typing unit being constructed and operating to print by compression; means for maintaining each typing unit in a position of rest; means for returning each typing unit to a position of rest 85 following its impression movement; and vertically spaced apart, bodily immovable pivots for the front toggle links, such pivots 90 being located forwardly of the bracket; said frame comprising a thereto fixed rear, transversely upstanding comb guide adjacent which the rear ends of the impression key levers are pivoted and which is formed with an opening for passage therethrough of a portion of a pivoted, universal bar and escapement dog carrier; said carrier projecting rearwardly into a space rearward of said rear comb guide and being in said space in 95 cooperative connection with a carriage escapement mechanism; such escapement mechanism mounted in said space; and located in said space, a paper carriage, a track therefor, and a paper carriage actuating 100 mechanism.

23. In a typewriting machine, the combination of a frame base having a front comb guide for key levers; a universal bar and dog carrying frame pivoted between its ends 110 and provided with a transverse, coiled return spring adjacent its pivots; and a series of typing units each comprising a rearwardly pivoted impression key lever bearing on the universal bar forwardly of the pivot 115 and a return spring for each the typing unit return springs being weaker than the return spring for the universal bar and dog carrying frame; each typing unit return spring serving to hold the members of the unit in 120 rest position and against operating movement and the return spring for said frame serving mainly to return a unit to position of rest after impression, both springs cooperating in the latter movement; said dog 125 and escapement carrying frame comprising an escapement dog mechanism; a horizontal escapement wheel and a therewith revoluble,

upstanding pinion and a paper carriage operatively connected with the pinion.

24. In a typewriting machine, a combination with a machine frame of a transverse series of dependent, pivoted, L-shaped rail carrying members, the under arms of which extend forwardly; a transverse rail fixed to said forwardly extending arms; a paper carriage mounted on the rail; a case shift key for shifting the rail; and a series of typing units, said rail being lengthwise troughed and carrying a series of anti-friction balls and the paper carriage comprising a member bearing on said balls and the rail and the ball engaging member of the paper carriage being provided with relatively movable, interlocking members.

25. In a typewriting machine, the combination of an open top frame having a front transverse comb guide, a rearward transverse comb guide forwardly of a transverse paper carriage space; a series of typing units each comprising an impression key lever mounted in the comb guides and pivotally connected with the frame; and a detachable cover having horizontal, rearward, side portions and therein between, forwardly extending, upstanding walls divergent in the forward direction and a rearwardly and downwardly sloping top wall; and in the paper carriage space, a paper carriage hav-

ing a platen; the upstanding and top wall of the carrier permitting visibility of a line being printed.

26. In the combination set forth in claim 25, an ink ribbon spool fixture mounted in each horizontal side portion of the cover.

27. In the combination set forth in claim 25, the open top frame having upstanding sides which with the front and rearward comb guides form a space forwardly of the carriage space; the typing units being in part housed in said space and concealed by the cover; and the rear of the cover terminating transversely at the front side of the carriage space; a paper carriage, case shiftable rail located in the carriage space; a case shifting key lever; a universal bar and dog carrying frame pivoted in the enclosed space and having its dog carrying end projecting rearwardly into the carriage space; and in the latter space an escapement wheel and therewith operating pinion for the carriage.

28. In the combination set forth in claim 27, a paper carriage structure carrying a laterally, vibratable carriage spring casing.

Signed at New York city in the county of New York and State of New York this 11th day of December A. D. 1922.

FRITZ R. FREDERICK.
